UNITED STATES PATENT OFFICE.

FRIEDRICK JOHANNING AND LEO RICHNOW, OF CORTEZ, COLORADO.

DITCHING-MACHINE.

1,016,998.

Specification of Letters Patent.

Patented Feb. 13, 1912.

Application filed July 19, 1911. Serial No. 639,304.

To all whom it may concern:

Be it known that we, FRIEDRICK JOHANNING and LEO RICHNOW, citizens of the United States, residing at Cortez, in the 5 county of Montezuma and State of Colorado, have invented certain new and useful Improvements in Ditching-Machines, of which the following is a specification, reference being had to the accompanying drawings.

This invention relates to ditching machines and has for its object to provide a suitable plow device which will make ditches, and throw the dirt therefrom to the 15 sides of the same, so that it will be entirely out of the way.

Another object of this invention is to provide it with an adjusting means whereby the angle, at which this device will dig 20 into the ground, can be suitably provided for.

A further object of this invention is to provide it with a knife which can be readily removed and sharpened whenever the same 25 is desirable.

A still further object is to arrange the device so that it can also be used for removing snow or mud from side-walks and streets.

Another object of this invention is to 30 have it so arranged and designed as to be readily manufactured at a comparatively low cost.

Other objects of this invention will become apparent as it is more fully set forth.

35 In the accompanying drawings which illustrate by way of example an embodiment of this invention: Figure 1 represents a plan view of a ditching device embodying this invention; Fig. 2 is a view in elevation; Fig. 3 is a front view.

Similar reference characters refer to similar parts throughout the drawings.

In the construction shown in the drawings, 1 represents a body or base portion of the ditching machine which is preferably constructed out of any suitable material into the shape shown in the drawings. The upper portion of this body being angularly tipped and its lower surface flat so as to 45 normally rest on the ground. The sides 2 of this body are extended upwardly and are cut at their end portions 3 in order to enable the earth that the device digs up to flow up by the sides 2 and out of the openings 3, being assisted in this action by the curved sides 4 of a plow member or mold

board. This plow member or mold board being secured to the body proper in any suitable manner.

In order to give the body proper of this 60 device its proper form and in order to keep down the cost of manufacture of the same, it is preferably made from a single piece of material cut into the necessary shape and bent into the form shown in the drawing. 65 A back is made, in order to reinforce the body, by extending down the material from the rear part of the upper portion and connecting it to the lower or ground portion of the machine. The outer or front portion of 70 the sides 2 of the body are slightly flared as is clearly shown in the drawings. The dotted lines in Fig. 2 indicate the general interior construction of the body and 4' are suitable means for securing the mold board 75 to said body.

To the front portions of the body and the sides of the same is secured a removable knife 5, that is bent to conform with the same. The bolts 6 being provided in order 80 to removably secure it to the body.

Handles 7 are attached to the back portion of the plow member 4, so that the whole device may be suitably guided by the operator, when the same is being used in digging a ditch. 8 being suitable braces for holding the handles in a rigid position.

Provided on the upper portion of the plow member 4 is an extending beam 9 that has its front portion 10 arranged to receive 90 a whiffle-tree, to which the power can be secured to pull the machine through the earth. The clevis 10 is provided with a number of holes 11 vertically disposed over one another, as is clearly shown in the drawings, 95 in order that the whiffle tree may be attached to different ones of them, so that a deeper ditch may be dug according to the conditions arising. The ditch being dug deeper as the whiffle tree is attached to the 100 holes nearest the top.

As the ditcher is drawn along the ground the knife 5 is dug into the same and causes the dirt therefrom to flow along the upper surface of the body portion between the 105 plow member 4 and the sides 2, and from thence out of the openings 3, which will deposit the dirt at the sides of the ditch that has been dug. Whenever it is desired to change the direction of the ditch in any way, 110 the operator suitably turns the ditcher by means of the handles 7.

Having thus described this invention it is claimed:

- 5 1. In a ditching machine, the combination of a body having its side pieces angularly disposed with respect to the ground, said side pieces having their upper rear portions cut away and a mold board disposed in said cut away portions and arranged to guide the material dug up by said machine off the rear side portions thereof.
- 10 2. In a ditching machine, a body comprising a single piece of material having a portion thereof arranged to form the base of the same, and the sides angularly set with respect thereto, a back integrally connected to the end of the last mentioned portion and
- 15

arranged to connect with said base, said side pieces having their rear upper portions cut away and a mold board disposed in said angularly arranged portion and having a draw bar integrally connected thereto, said mold board being arranged to guide the material dug up by said machine, to the rear side portions thereof.

In testimony whereof we hereunto affix 20 our signatures in the presence of two witnesses.

FRIEDRICK JOHANNING.
LEO RICHNOW.
